(57) **CLAIM**

The ornamental design for a vibration-proof platform for musical instruments as shown and described.

DESCRIPTION

FIG. 1 is a first perspective view of a vibration-proof platform for musical instruments showing our new design;

FIG. 2 is a second perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an enlarged view of area 9 in FIG. 1; and,

FIG. 10 is an enlarged view of area 10 in FIG. 1.

The dash broken lines illustrate portions of the vibration-proof platform for musical instruments that form no part of the claimed design. The dot-dash broken lines represent boundaries of the enlarged portions and form no part of the claimed design.

1 Claim, 10 Drawing Sheets
